(57) **CLAIM**

The ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the partially enlarged view of FIG. 1 that is included to more clearly depict the design from the front view (A) of FIG. 1;

FIG. 5 is the partially enlarged view of FIG. 2 that is included to more clearly depict the design from the front view (b) of FIG. 2; and,

FIG. 6 is the partially enlarged view of FIG. 3 that is included to more clearly depict the design from the front view (C) of FIG. 3.

The appearance of the animated user interface sequentially transitions between the images shown in FIGS. 1-3. The process or period in which image transitions to another forms no part of the claimed design. The broken line showing FIGS. 1-3 is for environmental purposes only and forms no part of the claimed design.

1 Claim, 6 Drawing Sheets
